UNITED STATES PATENT OFFICE.

WILLIAM B. CHAPMAN, OF NEW YORK, N. Y., ASSIGNOR, BY MESNE ASSIGNMENTS, TO CHAPMAN ENGINEERING COMPANY, OF MOUNT VERNON, OHIO, A CORPORATION OF OHIO.

GAS PRODUCER.

Application filed April 20, 1918. Serial No. 229,746.

To all whom it may concern:

Be it known that I, WILLIAM B. CHAPMAN, of 11 Broadway, New York city, in the county of New York and in the State of New York, have invented a certain new and useful Improvement in Gas Producers, and do hereby declare that the following is a full, clear, and exact description thereof.

The invention has for an object to provide a gas producer in which the bed of fuel is agitated in such a way as to bring about an even distribution of the fuel, and prevent caking thereof or the formation of blow-holes therein. A further object of the invention is to regulate automatically the relation of the agitator to the fuel bed in such a way that the agitator shall always be maintained in proper position.

Another object of the invention is to provide a mechanical fuel feed which will distribute the coal evenly over the surface of the fuel bed, and at any desired rate. Further objects and advantages of the invention will be in part obvious and in part specifically referred to in the description hereinafter contained, in which are disclosed certain embodiments of the invention, which embodiments however are to be considered merely as illustrative of the principle thereof.

30 In the drawings:

Fig. 1 is a vertical section of a gas producer constructed in accordance with the invention:

Fig. 2 is a section on line 2—2, Fig. 1 looking in the direction of the arrows:

Fig. 3 is a vertical section of another form of gas producer within the principle of the invention:

Fig. 4 is a top view of the structure shown 40 in Fig. 3:

Fig. 5 is an enlarged side view of the mechanism for mechanically feeding the fuel and associated parts:

Fig. 6 is a section on line 6—6 of Fig. 3, 45 looking in the direction of the arrows.

In Figs. 1 and 2 is shown a producer in which the base and top are stationary and in which a portion of the side wall is rotated. The base of the producer is represented at 50 15. Above the base 15, is located the rotatable portion of the side wall 16, having a supporting ring 24 which rests upon a plurality of rollers 21. A spur gear 23, which

in this instance is formed integrally with the ring 24, engages a driving pinion 25 on 55 shaft 26, and the side wall 16 is thus rotated slowly about a vertical axis. The upper side section 17 of the producer wall is supported by a number of pillars 20, which carry the rollers 21. Suitable devices for 60 charging the fuel into the producer and for removing the fuel therefrom are provided, but are not described in detail since they form no essential part of this embodiment of the invention.

The coal lies within the rotating side wall 16 at approximately the level indicated by the wavy line in Fig. 1, and an agitator 30 is employed to work in the upper portion of the coal and keep its surface levelled and loosened, and prevent caking of the coal or the formation of blow-holes in the fire bed. In the form shown in Figs. 1 and 2 the agitator 30 is provided with a pair of upwardly extending legs or supporting members 31, 75 thus making the agitator as a whole of a U-shaped form. These legs are joined to the agitator arm by couplings 32 which allow the parts to be easily removed from the producer, new parts to be fitted, and also 80 allow the agitator arm to be made of larger diameter or of different shape than the legs to secure the necessary amount of effect on the coal. The agitator is held stationary, or practically so, against rotary motion and 85 the coal within the side wall 16 rotates against it so that the agitator continually moves relative to the coal to bring about the results above mentioned. The legs 31 of the agitator are crooked or inclined oppositely to each other as shown in Fig. 2 and bear against guides or stops 33, which brace the agitator and its legs against the twisting moment, and thus determine the position 90 of the agitator with regard to horizontal movements, while still permitting the inclined legs 31 to ride upwardly or downwardly with regard to the guides according as the amount of resistance to rotation of the fuel bed produced by the agitator is 100 greater or less. If the fuel bed falls, the agitator 30 drops down by its own weight to proper position with regard to the fuel bed; if the supply of coal is such that the top 105 level of the fuel rises, the twisting moment upon the agitator causes it to ride up on the

guides 33 to a sufficient extent to maintain its proper elevation. Most of the weight of the agitator is borne by the lugs 33 against which it is forced with great pressure by the rotating fire bed. The legs 31 play vertically in channels 34 in the lining of the upper side section 17 of the producer, and at the top of the producer the legs extend through metal guides 36 and are enclosed in housings 37 allowing free vertical motion of the agitator. 38 represents a water pipe which enters one leg 31 by which water is caused to circulate through that leg and the horizontal arm of the agitator, and overflow from the other leg. At the upper ends of the legs circular lips 39 are provided, which prevent water from trickling down the sides of the pipes and reaching the fire through the guides 36 and channels 34. The guides 33 may also be water cooled, as by pipe 29. The guides 36 stand up in the bottom of the housings 37 so that water may collect in the housings without passing through the guides and this water overflows through openings 40 to chambers 41, in the producer top, from whence it is carried away by pipes 42.

In Figs. 3 to 6 is disclosed a form of apparatus in which the proper agitation of the fuel and proper regulation of the position of the agitator is brought about without necessitating the movement of any heavy parts of the apparatus. This is exceedingly desirable, since the cost of manufacture of such an apparatus is very much less than is the case when the producer walls are so made as to rotate; the cost of upkeep or repair is also very much lessened when only the agitator is made movable, and the heavy parts stationary. In Fig. 3 numeral 43 represents the side wall of the producer which, in this instance is stationary, and above which are located the producer top 44 and floor 45. A hollow supporting ring 46 having a water chamber 47, is set within the producer top 44, and carries a pedestal 48, which latter supports numerous parts of the apparatus later to be described.

The form of agitator disclosed in Fig. 3 comprises a substantially horizontal tubular arm 49 provided with a number of detachable stirring fingers 50 which project down into the fuel bed and prevent the formation of clinkers or cakes in the same. The arm 49 performs all the functions of a "slicer" and distributes the coal so as to maintain an even distribution of the same and to fill any blow-holes or hot spots in the fuel bed. The arm 49 is attached to a vertically disposed leg or stem 51, which latter is so rotated and guided as to bring about automatically a proper elevation of the arm 49. Adjacent its upper end the leg 51 carries a collar 52 which is fixedly connected thereto, said collar being provided with a pair of

spiral shoulders or fins 53. A worm gear 54 surrounds the leg 51 and its collar 52, and is rotatably mounted within an oil containing casing 55. The hub 56 of the worm gear 54 carries a pair of lugs 57 which engage the spiral fins 53 and thus rotate the agitator when motion is imparted to the gear 54. It will be seen that, in case the agitator is imbedded too deeply in the fuel bed, a greater resistance to rotation of the same will be encountered, so that the inclined bearing surfaces between fins 53 and lugs 57 will raise the agitator until its resistance to rotation is insufficient to raise it further. The particular elevation at which the agitator is maintained accordingly depends upon the amount of its resistance to rotation, a balance being maintained between the weight of the agitator acting downwardly, and its resistance to rotation acting upwardly against an inclined surface. The distance within the fuel bed at which the agitator will be maintained, can be adjusted by adding or removing weights 58 which rest upon the arm 51. With a given weight upon such arm the agitator will be automatically maintained at the proper elevation with regard to the fuel bed, but the fins 53 rise entirely above lugs 57 if the torsional strain on the agitator is too great thus releasing the agitator from its drive.

A cooling system for the agitator may be carried out by means of an inlet pipe 59 which is connected to a pipe 60 within the agitator leg 51. Pipe 60 leads to a similar pipe 61 within the agitator arm 49, the latter pipe being provided with suitable openings 62 so that the cooling water passes through pipes 59, 60, 61 through openings 62, and is returned through the annular spaces between pipes 49, 61 and 51, 60 to the discharge nozzles 63 adjacent the upper end of the leg 51. From this point the cooling water falls into a reservoir 64 in the pedestal 48, from whence a part of it passes through pipe 65 to the interior of a coal deflecting ring 66 which returns it to a pipe 67, through additional pipes 68 and 69. The remainder of the cooling water passes directly from chamber 64 through pipes 68 and 67 to one supporting leg 69 of a bearing member 70 for the leg 51. The leg 69 together with a pair of legs 71, forms a tripod support for the bearing 70, and the water is led from the interior of such bearing to the chamber 47, by means of the two hollow legs 71. From the chamber 47 the water is drawn off through pipe 72.

In order to rotate the agitator, there is provided a motor 73 which is mounted on top of the oil containing gear casing 55. The motor pinion 74 engages a spur-gear 75 adjacent one end of a shaft 76, which latter is journaled in suitable bearings 77. Ad-

5 jacent its other end the shaft 76 carries an eccentric 78 cooperating with an eccentric rod 79 in the usual way. The outer end of the rod 79 is pivoted to a link 80 mounted upon a shaft 81, which also carries a ratchet wheel 82, the link 80 carrying a pawl 83, so that as the eccentric rod 79 reciprocates the pawl 83 intermittently turns the ratchet wheel 82, and therefore the shaft 81. A 10 worm 84 is also carried by the shaft 81, and engages the worm wheel 54 so as to bring about the desired rotation of the agitator.

15 The invention also comprises means for mechanically feeding coal to the fuel bed so as to effect the proper rate of supply and distribution. According to present producer practice, it has not been feasible to build an apparatus of over about nine feet 20 diameter and feed the coal by means of a centrally located bell, owing to the fact that the bell would have to be of such large diameter as to prevent the desired amount of coal from falling to the area directly 25 under the bell.

30 Furthermore, in producers of the type shown in Figs. 3 to 6, it has been the practice to rotate the fire bed under the feed in order to distribute the fuel evenly over the whole 35 surface of the fuel bed. Thus the distribution of fuel would not be uniform until the fuel bed had wholly completed one revolution with respect to the feeding apparatus. The above method of operation has the disadvantage that, since the fuel bed rotates only about once in one-half an hour, the temperature at different points around the fuel bed was very uneven.

40 According to this invention the coal is fed simultaneously over the different portions of the fuel bed, so that the distribution of coal does not depend on rotary movement of the fuel bed. Also, in a producer of this type the space directly above the center of the fuel bed is taken up by the agitator leg and associated parts so that it is necessary to provide a fuel feed which is located at one side, and which nevertheless 45 will distribute the coal simultaneously over the entire fire bed, including the portions of such bed which are directly under the agitator and its associated parts. To bring about the above results, a fuel receiving casing 85 is employed which has a chute 86 leading to the interior of the pedestal 48. An inclined shelf 87, in the interior of the pedestal 48, conducts a portion of the fuel to the far side of the pedestal, so that the portion of the fuel bed to which free passage 50 of the coal is prevented by the ring 66 and bearing 70, will still receive its share of supply. The shelf 87 preferably is made tapering (Fig. 6) so that a certain amount of fuel will be delivered at all points around 55 the periphery thereof. The fuel delivered

from the central portion of the chute 86 will strike against the pipe 51^a (Fig. 6) which encloses the agitator leg 51, and this fuel will fall to the near side of the fuel bed, while the fuel which is delivered from 70 the sides of the chute 86 will pass around toward the far side of the shelf 87 so as to reach the far side of the fuel bed. The funnel-like surfaces of the rings 46 and 66, in combination with the shelf 87, will project 75 coal over the outer parts of the fuel bed so as to effect proper distribution of the coal in this area. In order to supply the center of the fuel bed properly, a plurality of deflectors 88 are provided on the ring 46, which 80 direct a certain amount of the falling coal to the central area of the fuel bed. Deflectors 89, having handles 90 (see Figs. 3, 5 and 6) adjustable by means of nuts 91, may also be placed within the chute 86 so as to 85 regulate the amount of coal which will pass to the far side of the pedestal 48. In the above manner the question of properly feeding the fuel with a centrally disposed agitator leg and supporting parts is solved. 90

95 The fuel receiving casing 85 encloses a fuel feeding drum 92, which is mounted upon a shaft 93. Such drums are liable to stick owing to the tarryness of the gas developed within the producer, and to prevent this the distance between the walls of the casing and the drum is made adjustable. In the present form, this is accomplished by employing a drum and receiving casing of frusto conical shape, so that the drum can 100 be moved axially to separate it from the casing wall as much as is necessary. As shown in Fig. 6, a screw 94 having an operating handle 95 may be threaded into engagement with a bracket 96 in order to 105 force the drum as close to the walls of the casing as desired. Shaft 93 is made to project beyond the smaller end of the casing 85, so that if the drum should stick, screw 94 may be turned back from engagement with 110 the opposite end of shaft 93, and the projecting end struck as by a hammer, to dislodge it. The space between the drum 92 and the casing 85, must not be larger than 115 is necessary lest the leakage of the producer gas at this point be too great. It is therefore necessary to so regulate the screw 94 as to effect a balance between the two requirements.

120 In order to actuate the drum, an adjustable crank 97 (Fig. 5) upon the end of shaft 81 is provided, such crank being pivoted to a driving rod 98. The shaft 93 pivotally supports a forked link 99 which encloses a grip wheel 100, and a cam 101, pivoted to the link 99 at 102, grips the wheel 100 during each stroke of the crank 97 so as to intermittently turn the wheel 100 and therefore the drum 92. It often happens that 125 motion of the drum 92 is prevented by some 130

obstruction fed in with the coal, and to prevent damage to the parts in case this should happen, a releasable drive is provided for the drum. In the present instance this result is brought about by making the driving rod 98 in two parts, which respectively have a pin 103 in one engaging a hole 104 in the other, but which are ordinarily fixedly connected to each other by means of a 10 weighted lever 105 attached by a clamp 106 to one part, and having a tapering lug 107 engaging a tapering pin 108 on the other part. By means of the above construction the two parts ordinarily move together, but 15 if rotation of the drum should be prevented, the tapered lug 107 will ride over the pin 108, while still exerting enough force on the pin during each stroke to again start the drum as soon as the obstruction is removed. 20 If desired a spindle 109, provided with projecting pins or teeth 110, may be provided above the drum 92 in order to prevent arching of the fuel above the same, the said spindle being rotated by the gear 111 25 fixed to it, and engaging a further gear 112 (Fig. 6) on the shaft 93.

While certain specific forms of the invention have been described, it is obvious that many changes may be made therein without 30 departing from the scope of the invention as defined in the following claims.

I claim:

1. In a gas producer, an upwardly and downwardly movable agitator, means for causing relative rotation between said agitator and the fuel bed, and means for screwing the agitator upwardly and downwardly according to the torsional force produced thereupon by such relative rotation. 40 2. In combination, a producer fuel bed and a fuel agitator, mechanism for rotating one relative to the other, said agitator being movable toward and away from the fuel, and a member bearing against a part 45 of the agitator during such relative rotation, an inclined bearing surface being provided between the agitator and said member, whereby the elevation of the agitator is controlled by the amount of resistance 50 to such relative rotation produced by the agitator.

3. In combination, a producer side wall and a fuel agitator, mechanism for rotating one relative to the other and a guiding 55 means for the agitator changing its elevation in case of variation in the amount of torsional resistance to such relative rotation produced upon the agitator.

4. In combination, a producer side wall 60 and a fuel agitator, mechanism for rotating one relative to the other, a guide for the agitator permitting movement of the latter toward and away from the fuel, said agitator and its guide having inclined engaging 65 surfaces, whereby the elevation of the agi-

tator is controlled by the amount of resistance to such relative rotation produced by the agitator.

5. In combination, a producer side wall and a fuel agitator, mechanism for rotating one relative to the other, said agitator being provided with an upwardly extending leg, and a member bearing against said leg during such relative rotation, an inclined bearing surface being provided between the agitator and said member, whereby the elevation of the agitator is controlled by the amount of resistance to such relative rotation produced by the agitator. 70 75

6. In combination, a producer side wall and a fuel agitator, mechanism for rotating one relative to the other, said agitator being provided with an upwardly extending leg, a guide for the agitator permitting movement of the latter toward and away from the fuel, said agitator and its guide having inclined engaging surfaces, whereby the elevation of the agitator is controlled by the amount of resistance to such relative rotation produced by the agitator. 80 85 90

7. In combination, a producer side wall and a fuel agitator, mechanism for rotating one relative to the other, said agitator being provided with an upwardly extending leg, a guide for the agitator surrounding 95 said leg, a fin and inclined spiral shoulder engagement being provided between the two.

8. In combination, a fuel agitator, mechanism for rotating said fuel agitator, an inclined bearing surface being provided between the agitator and a part engaged by it during its rotation, whereby the elevation of the agitator is controlled by the amount of resistance to rotation thereof. 100 105

9. In combination, a producer side wall, a fuel agitator therewithin, a mechanism for rotating said fuel agitator, a guide for said agitator determining the position of the same with regard to horizontal movements, said agitator and its guide having inclined engaging surfaces, whereby the elevation of the agitator is controlled by the amount of resistance to rotation thereof. 110

10. In combination, a fuel agitator, mechanism for rotating said fuel agitator, and a guiding means for the agitator controlling its elevation by the amount of resistance to rotation of the agitator. 115

11. In combination, a fuel agitator, the agitator being provided with an upwardly extending leg, and a gear surrounding said leg for rotating the agitator, a spiral fin and shoulder engagement being provided between said leg and gear, whereby the elevation of the agitator is controlled by the amount of resistance to rotation thereof. 120 125

12. In combination, a fuel agitator, the agitator being provided with an upwardly extending leg, and a gear surrounding said 130

leg for rotating the agitator, an inclined bearing surface being provided between the agitator and a part engaged by it while turning, whereby the elevation of the agitator is controlled by the amount of resistance to rotation thereof.

13. In a gas producer, a hollow pedestal located above the fuel bed, an agitator leg extending upwardly into said pedestal, means at one side of said pedestal for feeding fuel to the interior thereof, and a shelf in the interior of said pedestal leading toward the other side thereof and adjacent the fuel feeding means, whereby a portion 15 of the fuel fed will be projected to said other side of the pedestal, and a portion of the fuel prevented from passing to said other side, by said agitator leg.

14. In a gas producer, a hollow pedestal located above the fuel bed, an agitator leg extending upwardly into said pedestal, a fuel receiving casing at one side of said pedestal adapted to feed fuel into the interior thereof, and a shelf on the inner wall 25 of the pedestal tapering in width toward the other side thereof and adapted to lead a portion of the fuel to said other side.

15. In a gas producer, a top wall having an annular funnel-like opening therein 30 adapted to direct the fuel into the outer part of the fuel bed, and a deflector adapted to direct a portion of the fuel into the central area of the fuel bed.

16. In a gas producer, a top wall having an annular funnel-like opening therein 35 adapted to direct the fuel into the outer part of the fuel bed, a deflector adapted to direct a portion of the fuel into the central area of the fuel bed, and supporting members for a fuel agitator obstructing direct passage of the fuel to said central area.

17. In a gas producer, a rotatable agitator, means for supporting said agitator, said means being centrally located within the 45 producer, fuel feeding means for delivering fuel and means for deflecting fuel to parts of the fuel bed that are screened by said supporting means.

18. In a gas producer, a rotatable agitator, means for supporting said agitator, said means being centrally located within the producer, fuel feeding means for delivering fuel at a level above said supporting means,

and means for deflecting fuel to parts of the fuel bed that are screened by said supporting means. 55

19. In a gas producer, a fuel feeding passageway having agitator supporting parts extending therethrough a fuel chute leading to said passageway, and means for guiding 60 a portion of the fuel to the portion of the passageway obstructed by said supporting parts.

20. In a gas producer, a fuel feeding passageway having agitator supporting parts 65 extending therethrough and thereunder, a fuel chute leading to said passageway, and means for guiding a portion of the fuel to the portion of the passageway obstructed by said supporting parts, and deflectors for 70 guiding a portion of the fuel to the part of the fuel bed underneath said supporting parts.

21. In a gas producer, a fuel feeding passageway having agitator supporting parts 75 extending therethrough, and means for feeding fuel evenly to all portions of said passageway and to all portions of the fuel bed.

22. In combination, a fuel agitator, the 80 agitator being provided with an upwardly extending leg, and a gear surrounding said leg for rotating the agitator, a fin and spiral shoulder engagement being provided between said leg and gear, whereby the elevation 85 of the agitator is controlled by the amount of resistance to rotation thereof, said engagement being released when the resistance is too great, so as to release the agitator. 90

23. In a gas producer, devices for effecting a feed of fuel to the space above outer zone of the fuel bed, and means for deflecting a portion of the fuel so fed to the central area of the fuel bed. 95

24. In a gas producer, a fuel feeding chute, an agitator extending beneath the same having an upwardly projecting stem, a bearing for said stem located above the fuel bed, and a supporting leg for said 100 bearing having an inwardly inclined surface disposed in the path of fuel fed from said chute.

In testimony that I claim the foregoing I have hereunto set my hand.

WILLIAM B. CHAPMAN.
